UNITED STATES PATENT OFFICE.

THOMAS I. RANKIN, OF PHILADELPHIA, PENNSYLVANIA, ASSIGNOR TO THE
ABRAM COX STOVE COMPANY, OF SAME PLACE.

WATER-HEATER.

SPECIFICATION forming part of Letters Patent No. 663,363, dated December 4, 1900.

Original application filed April 8, 1899, Serial No. 712,252. Divided and this application filed September 12, 1900. Serial No. 29,793. (No model.)

To all whom it may concern:

Be it known that I, THOMAS I. RANKIN, a citizen of the United States, residing in Philadelphia, Pennsylvania, have invented certain improvements in Water-Heaters, (being a division of an application for patent filed by me on April 8, 1899, under Serial No. 712,252,) of which the following is a specification.

The object of my invention is to construct a gas-heater for heating water which can be used in place of the ordinary water-back of a range or can be used in addition to said water-back, as desired.

This application is a division of an application filed by me on the 8th day of April, 1899, Serial No. 712,252.

In the accompanying drawings, Figure 1 is a longitudinal sectional view of my improved water-heater on the line 1 1, Fig. 2; and Fig. 2 is a transverse sectional view on the line 2 2, Fig. 1.

A is a water-chamber made of cast metal and preferably in a single piece. In the present instance it is quadrangular in form, having side bars a and cross-bars a' at top and bottom and intermediate cross-bars a^2 . All the bars are tubular and are so shaped and arranged as to provide for the ready circulation of the water to be heated. By making the bars tapered in cross-section accurate castings can be readily produced. The cross-bars a^2 are staggered, as shown, and the end bars a are corrugated to correspond therewith. This arrangement deflects the products of combustion, so that all portions of the casting will be subjected to the direct action of the same.

The water-chamber A is inclosed within a casing B. This casing in the present instance consists of a lower frame B', a cap-plate b, sides b', and end plates b². The cap-plate b is flanged and the side plates are secured to the said flange and to the bottom plates by screw-bolts or rivets. In the present instance the side and end plates are made of a single sheet of ornamented metal lined with a non-conducting material, so that heat will be retained in the water-heater.

The cap-plate b has a flue-opening c, above which is a short stack C to carry off the waste products of combustion.

Forming part of the lower frame B' is the cap d of the burner D. Arms d' connect the cap with the portion of the frame secured to the casing. Secured to the cap d is a trough-shaped bottom section D', the edges of this section fitting snugly against the flanges of the cap, as shown in Fig. 2, and screw-bolts d² pass through the cap and trough-section, holding the parts together.

The cap d has a series of perforations i for the escape of gas. A gas-pipe I is connected to one end of the burner, as shown in Fig. 1. The pipe is provided with the usual valve (not shown) and an air-valve i'. Air and gas are mixed at the valve i', and the mixture enters the burner, escaping through the perforations i and mixing with a certain quantity of air entering through the space between the flange of the frame B and the depending cap b.

At each upper corner of the water-chamber A are threaded bosses e e, and in the lower cross-bar a' are threaded bosses e' e'. The water-pipes E E', leading to the boiler, are coupled to one of the upper bosses and to one of the lower bosses. The openings in the other two bosses are closed by suitable plugs. By providing the bosses as shown the water-heater can be used either right or left handed.

My improved water-heater can be attached to the circulating-pipes of an ordinary range using a boiler and water-back or may be used independently of the water-back, if desired.

As soon as the water in the boiler or other receptacle reaches a certain temperature the gas can be turned off, thus economizing in the fuel. The water-heater may be coupled to a supply-pipe at any point desired and water heated independently of a range or a water-heater at the range.

I claim as my invention—

1. A casting having tubular corrugated side bars and tubular cross-bars communicating with the tubular side bars, said cross-

bars being staggered, in combination with a casing inclosing said casting and a burner under the said casing, substantially as described.

5 2. The combination of a casting made in a single piece and having tubular corrugated side bars and tubular cross-bars communicating with the tubular side bars, the said cross-bars being staggered and tapered, with 10 a casing inclosing the said water-chamber, and a burner under the said casing, substantially as described.

3. The combination of a water-chamber, a casing inclosing said water-chamber, said 15 casing consisting of an open base-frame, a top plate having a flue-opening therein and flanged, with a side plate or plates secured to the base-frame and the flanges of the top plate, a longitudinally-arranged burner directly under the casing, the cap of the burner forming part of the base-frame of the casing, the trough-shaped lower portion of the burner being secured to the cap, and a gas pipe 20

coupled to the said burner, substantially as described.

4. The combination of a water-chamber, a casing in which the water-chamber is mounted, said casing having a base-frame, a burner situated under the casing, the cap of said burner forming part of the base-frame and 30 connected thereto by arms, the cap having a series of perforations for the escape of gas, the trough-shaped section of the burner being secured to the cap by bolts or other fastenings, and a gas-pipe coupled to said burner, the space between the cap of the burner and the casing allowing for the passage of air to mix with the gas, substantially as described.

In testimony whereof I have signed my name to this specification in the presence of 40 two subscribing witnesses.

THOMAS I. RANKIN.
